BOOK HEADBANDING MECHANISM

Application filed August 21, 1931. Serial No. 558,500.

This invention is a novel book headbanding mechanism, or that class of apparatus wherein ornamental strips or "headbands" are applied at both the head and the foot 5 ends of the back of the book, this step usually following the application of adhesive to the book back, and being usually followed by the application of a "backlining" or paper backing, and thereafter the insertion of 10 the book into its cover or "case". A typical example of an apparatus for performing the gluing, headbanding, backlining and other operations in sequence upon each of a succession of round back books caused to travel 15 through the apparatus is disclosed in a prior application of Bredenberg Serial No. 219,712, filed September 15, 1927, which may be referred to for various general matters and details which have been omitted herefrom as 20 not essential to the disclosure of the present improvement. Said prior application discloses a machine wherein the succession of books is advanced edgewise and in a step by step manner, with the rounded backs of the 25 books beneath, and the successive books carried in a succession of clamps connected in a train; but the present invention is not confined to use with such type of machine, since the book might be carried with its back above; 30 and by means other than a train of clamps for the guidance and advancing movement of the books, which might in some cases be continuous in character, although preferably intermittent as in said application. The present 35 invention, like the prior application, is preferably automatic, but is not confined to an apparatus wherein the preceding gluing and the succeeding backlining operations are automatic, since the present invention is directed 40 more especially to the headbanding step.

The general object of the present invention is to improve the efficiency and the accuracy of operation in the application of headbands to round back or other books. A special object is to improve the devices handling the 45 small headbands or strips and accurately aligning or registering them to each book during application thereto. Further objects and advantages will be pointed out in the following description of an illustrative embodiment.

ment of the invention or will be apparent to those skilled in the subject. To the attainment of the objects and advantages referred to the invention consists in the novel book headbanding mechanism, and the novel features of operation, combination and construction herein illustrated or described.

In the accompanying drawings Figure 1 is a perspective elevation of a headbanding mechanism embodying the present invention, 60 and indicating a succession of books carried by an intermittently advancing train of clamps, but omitting the clamp driving means as the same is sufficiently indicated in said prior application.

Fig. 2 may be described as a front elevation of the mechanism shown in Fig. 1, omitting the book carrying clamps.

Fig. 3 is a right elevation of the mechanism shown in Figs. 1 and 2, with certain longitudinal parts of the machine shown in transverse section, and certain other parts broken away to show details of construction.

Fig. 4 is a perspective elevation on a larger scale of the feeding, severing, applying and registering devices adjacent to the rear or left end of the book back.

Referring first to certain general parts, each book clamp 10 may comprise a front clamp plate 11 and a back clamp plate 12, 80 the successive clamps being hinged or articulated together in a well-known manner and guided on longitudinal elements generally indicated at 13. Each back clamp plate may advance toward the right in a fixed path. Each front clamp plate is slidably fitted to the back plate by a spring pressed device 14, tending to hold the clamp plates pressed strongly upon the book B, but permitting separation or forward movement of the front plate to receive and discharge the book.

As is usual in clamp train machines, each book B is preferably registered in the clamp by actual contact with some part of the clamp, for example with the device 14, or by a special positioning or gaging pin 15, arranged near the rear or left end of the clamp, the clamps being movable toward the right in a step by step manner, each book being held in its clamp with its rear or left edge 100

in contact with the pin 15, and with its rounded back extending longitudinally in the direction of book travel and projecting below (or above) the clamp, accessible for 5 the operations to be performed. Conveniently the positioning pin 15 may be removably inserted through apertures 16 formed in both plates of each clamp, and there may be a second pair of apertures 17 spaced there- 10 from so that the pin can be shifted from one pair of apertures to the other, according to whether the machine is handling relatively short or long books; so that a short book 15 may take a position somewhere near the middle of the clamp.

In the drawings the clamps are shown as carrying relatively short books B, their rear edges contacting the pins 15 in the apertures 16, but other means may be employed for 20 holding and advancing the books from position to position. Whatever type of book holding or conveying means is employed there is a likelihood of the successive books coming occasionally to the operating place 25 or station in not exactly the correct position. This may be due to slight variations or lost motion in respect to the travel of the book advancing means to the headbanding position, or it may be due to accidental variation 30 of the position of each book in the clamp or other advancing means. Any such variation in longitudinal position, even though relatively small in amount, may be highly objectionable in connection with the application 35 of the headbands to the books, as it is practically vital that each headband, being an ornamental strip or finish to each book back, shall be correctly registered or positioned with relation to the top and bottom 40 ends of the book, that is, to the forward and rearward ends of the book held and advanced in the manner disclosed. With the present invention this requirement is met by a construction of headbanding mechanism 45 wherein, during the pause of each book, the mechanism is caused to adjust itself to the book, through one or two feelers or contacters which detect and determine the position 50 of one or both ends of each book, and thereupon control the headband applying devices or the headbands themselves so that the headbands will be positioned upon the books in the exactly correct locations desired, giving 55 a uniform and satisfactory product. The drive of the conveyor or clamp train may be coordinated with the headbanding mechanism as in the prior application, through a main shaft 19, preferably continuously rotated.

60 Referring to the headbanding mechanism, the extended base of the machine may have mounted upon it an opposite pair of standards 20. Extending frontwardly from the standards are brackets 21 giving support to 65 an axle 22 on which are mounted a pair of

supply spools 23 carrying the headband supply strip H'. The standards 20 extend upwardly and are suitably shaped to carry the various shafts, axles and other elements of the mechanism. 70

Two applying devices are shown, one at the left and the other at the right end of the mechanism, acting upon the rear and forward ends respectively of the book. Each applying device preferably comprises two 75 distinct elements, on the same general principles as said prior application, namely a shaper or concave forming member 26 which presses a substantial portion or the entire length of the headband upwardly firmly 80 against the rounded book back, and a holder or suction member 27 in the form of a head or narrow nozzle adapted to receive and hold each individual headband during the movement or lifting thereof to the book but preferably easily yieldable as the shaper comes 85 into action. The combined elements 26 and 27 are shown mounted on a carriage 28 or 28^a, the latter at the right or forward end of the mechanism, the two carriages being arranged to rise and descend, also to swing 90 inwardly and outwardly, that is, backwardly and frontwardly, in unison, as will be described. Each carriage is continued downwardly as an extension or arm 29 or 29^a, 95 these terminating in a hub 30 or 30^a both mounted on an axle system arranged to rise and descend.

The axle of the carriage hubs 30, 30^a may have the following special construction to 100 permit adjustments for varying book lengths. The left hub 30 is mounted on a hollow axle part or sleeve 31, between collars 32 held by set screws 33, the sleeve and collars being non-rotatable but the hub able to rock thereon, and the hub being adjustable longitudinally by loosening the set screws and resetting the collars according to the setting of the pin 15 in the book clamp. The hub 30^a is confined 105 between collars 32^a pinned to an axle part 34 which at its left end is extended, reduced and threaded at 35, this extension passing through the hollow axle part 31 and having screw engagement therewith. Upon turning the axle part 34, 35 it will adjust itself rightward or leftward and correspondingly adjust the right carriage 28^a. 110

For conveniently adjusting the carriage 28^a to any desired position, according to the varying lengths of books, and at the same time making certain other adjustments to correspond, a threaded shaft 37 is shown, carrying a hand wheel 38 at its right end, and turning in a bracket 39. The shaft may be engaged by a nut 40, thus shifted right and left to adjust the severing and feeding devices as will be described. The threads on the shaft 37 may have the same pitch as those on the axle 35, and they may be connected to turn in unison as follows. On the shaft 37 is 115 120 125 130

shown a sprocket 42 engaging a chain 43 which in turn engages a sprocket 44 on an axle 45, with a second sprocket 46 connected thereto and in turn connected by a sprocket chain 47 with a sprocket 48 which turns the axle part 34. By this arrangement the turning of the hand wheel 38 effects the adjustment of the hub 30^a and carriage 28^a, adapting the mechanism to the length of the book. The 10 rising and falling movements of the axle system 31-35 and the carriages will be later described.

Corresponding with the threaded shaft 37 which shifts the nut 40 to adjust the feeding 15 and severing devices at the right, there is shown at the left a threaded shaft 51 mounted in a bracket 52 and having a head 53 by which it can be turned by wrench, the shaft engaging a nut 54 from which the severing and feeding 20 devices take their adjustment. The manual adjustment of the left carriage 28 is made by shifting the collars 32, as already described. These two complementary adjustments at the left end are not made so conveniently as those effected by the hand wheel 38 at the right end, for the reason that the shift of the pin 15 in the clamp is rarely necessary, while various miscellaneous variations of book length may be wholly taken care 25 30 of by the adjustments at the right or forward end by the hand wheel 38 as described.

Returning to the applying device, supported on each carriage, consisting of shaper and suction holder, the shaper 26 is shown 35 as a thin plate or bar, with its top edge concave, and mounted on the carriage to rise and fall therewith, by the following mounting. The shaper plate is shown as closely adjacent the outer side of the suction head 40 but mounted independently on the carriage. The lower end of the shaper 26 is shown as 45 enclosed between a small upright fork 55 and the upper portion of a yoke 56, all three of them united by a shouldered bolt which holds the fork rigid with the yoke, but permits a slight lateral play of the shaper, limited however by a pin projecting from the shaper between the arms of the fork. The lower end of the yoke is rigidly bolted to the upper end 50 of a plunger 57 having a frontwardly extended head overlying a horizontal portion of the carriage 28 and having an interior rod extending within a recess in the carriage, as seen in Fig. 3, with a strong compression 55 spring 58 confined below the plunger, tending to lift it relatively to the carriage, and thus holding the shaper in its operative position, under the control of a limiting bolt 59. By this arrangement the shaper is made to 60 rise and fall with the carriage, in a substantially rigid manner, but the strong spring 58 permits a slight downward yielding or cushioning without detracting from the effectiveness of the pressure on the headband, 65 and the relation with the fork member 56 per-

mitting a slight transverse play assisting the shaper to adapt itself to the curvature of the book, the fork also serving as a convenient means for confining and initially adjusting in proper position shapers of various width 70 and curvature, which should be readily interchangeable with variations of books.

The suction holder 27 is shown as having a suction opening or nozzle 60 for the headband, arranged at the top side of the holder, 75 which has a horizontal extension or shank 61 constructed with an air channel 62 leading to the suction opening. The holder shank 61 is connected by a hollow pivot or stud 63 with the upper portion of the carriage 28, which is 80 provided with extension side plates 64 to enclose the shank and afford bearing for the stud.

The suction nozzle 60 is for the purpose of holding securely each small headband during and after severance and up to the time of application to the book. As books may have varying thickness the nozzle opening is preferably adjustable in length and for this purpose a narrow slide 66 is arranged in a groove 85 at the top side of the holder, so that it can be adjusted more or less in or out and thus determine the length of the suction opening or slot.

The suction holder and its shank may be 90 yieldingly supported in the horizontal position shown, and there is indicated a spring 67 arranged to swing upwardly the holder about its pivot stud, this movement being limited by a stop or pin 68 as seen in Fig. 3. 100 By this arrangement when the rising carriage brings the headband to the book the book acts as a stop and on continued rise of the carriage the holder 27 yields relatively downward, 105 while the concave shaper 26 continues to rise and to press the headband firmly into contact around the back of the book, the suction having ceased as the headband contacted the book. The holder spring 67 is of far lighter effect than the shaper spring 58, the function of the holder being completed when the headband meets the book, while the function of the shaper is to afford strong pressure thereafter.

The suction action and control may be substantially as follows. A pneumatic hose 72 is shown extending from each of the hollow studs 63 of the respective suction holders downwardly to a common pipe 73 which in turn is shown connected to a pipe 74 which extends toward the back of the mechanism and is connected by a pipe 75 with a control valve 76. The control valve may be substantially similar to that shown in said prior application at Figs. 12 and 13, comprising a sliding bar or horizontal plate 77 having a suction passage open in one position and a relief passage open to the atmosphere in another position, the suction passage serving to 115 120 125 130

connect the vertical pipe 75 with a pipe 80 leading to an air pump.

The stem 82 of the valve slide is indicated as being pressed backwardly, or to the right in Fig. 3, by a spring 83 acting upon the head 84 of the stem, this head sliding in a fixed part and carrying a cam roll 85 bearing against the periphery of a cam 86 on the main shaft 19. In the position shown in Fig. 3 the valve is thrust forwardly and the suction is in effect, holding the headband upon the holder.

The various trains of connections are not shown in corresponding positions in the several figures, but each train from the shaft cam to the terminal instrument is completely shown, and the description gives the order or cycle of operation, so that one versed in the art can correctly design the operating cams and attach them to the main shaft in correct relation.

The bodily lifting and lowering of the headband applying devices may be effected as follows. The carriages 28 and 28^a and their extensions 29 and 29^a with hubs 30 and 30^a are supported in upright position on the horizontal axle system 31-34 already described. This is a floating axle mounted at the front or swinging ends of lever arms 90 fulcrumed on the axle 45, which axle may act as a rock shaft, having a rearwardly extending rock arm 91 carrying a follower or roll 92 bearing against a cam 93 on the main shaft 19. The axle part 31 is fixed against rotation in the left lever arm, being internally threaded and acting as a fixed nut for the threaded extension 35 of the axle part 34, which latter turns in the forked end of the right lever arm, and has a keyway by which the sprocket 48, between the fork ends, maintains a sliding keyed engagement with the axle.

In the position shown the front ends of the arms 90 are in downward position, the cam roll being in lifted position, and a spring 94 may be arranged at each side to hold the parts in this position, with the roll pressed against the cam, and the cam being adapted upon further rotation, to force down the roll and thereby lift the front arms, the carriages and the headband applying devices, to place the headbands upon the exposed back of the book.

Preferably the applying devices, the shaper and the holder, assume a back position during the reception and severing of headbands, but with the carriages shift or swing forwardly therefrom during the rising motion to apply the headbands to the book. This permits the shearing type of severing device to be used, and avoids conflict with the front blade by the applier and headband in the lifting motion.

The following described device may be employed to cause the forward swinging of the carriages during their elevating move-

ment. In a boss or enlargement formed at the lower part of each carriage, at the top of the extension arm 29 or 29^a, is mounted a bolt or stud 99 extending rearwardly, the rear end of each bolt carrying a follower or roll 100 adapted to move along the surface of a fixed cam 101. Each of the cams 101 is of substantial width, as seen in Fig. 2 so as to cooperate with the follower in all adjustments for book length, and each cam has a lower and an upper surface, with a decided incline between them, so that in rising from the headband receiving position the carriages and applying devices will at the same time move forwardly as indicated by the dotted lines in Fig. 3, the forward swing occurring early enough for the applier and headband to clear the front or top severing blade to be described.

The headband strip H' may pass from the supply reels 23 and thence between guides and under a guard plate 105 and thence upwardly and rearwardly, each passing around an idler pulley 106 or 106^a. The feeding devices at the forward and rearward ends are substantially duplicated, the former carrying similar reference numbers sometimes with the exponent ^a, and each set being adjustable independently and in a different manner from the other set. The construction of the forward set will be first described.

The idler 106^a may constitute a guide pulley, with flanges, steering the headband strip correctly to the feed rolls, and itself adjustable longitudinally for this purpose. The headband passes from the guide pulley horizontally forward between a lower feed roll 108^a and an upper feed roll 109^a. The lower feed rolls may be mounted upon so as to turn with a shaft 110 and may adjustably slide thereon, while the upper feed rolls are mounted upon a shaft 111 on which they may slide. As shown in Fig. 3 the upper shaft 111 may be mounted on rock arms 112 having a fixed fulcrum 113 permitting the upper feed rolls 110 to be lifted bodily at will for insertion of headband strip, gravity normally holding them down upon the lower rolls.

The rearward or left pair of rolls 108, 109 are adapted to be adjustably shifted bodily along the direction of book travel by means of the threaded shaft 51 manually rotatable to give an adjustment to correspond with the position of the rear end of the book determined by the position of the clamp pin 15. The connections for this adjustment may comprise grooved hubs 115 on the feed rolls, with fingers 116 engaging them extending from the adjusting or knife carriage 137 to be described.

Likewise the forward or right feed rolls 108^a, 109^a are adapted to be bodily shiftable along the direction of book travel, by means of the threaded shaft 37 turned by the hand wheel 38, which also has sprocket connections 130

for readjusting lengthwise the position of the carriage and headband applying device. The connection by which the shaft 37 effects the adjustment of the forward feed rolls may 5 comprise grooved hubs 115^a on the feed rolls with fingers 116^a engaging them, extending from the carriage 137^a to be described.

In order to turn in unison the two feed shafts 110, 111 they are shown at the left 10 end as provided with intermeshing gears 121, 122. By rotating the shaft 110 all of the feed rolls are turned in unison. This actuation may be substantially as in said prior application, and briefly referred to as follows. 15 Loose on the shaft 110 is indicated a gear 124 constituting one member of a roller clutch or one-way drive device, the other member consisting of a clutch member 125 fast on the shaft 110. Below the toothed clutch member 124 is a horizontal rack 126 reciprocable to oscillate the clutch member, thereby causing intermittent forward rotation of the shaft 110 and the four feed rolls. The parts thus far described are shown in Fig. 2. The 20 rack has a rearward extension 127 shown in Fig. 3, this being moved forwardly and rearwardly by an upright rock lever 128 fulcrumed on a rock shaft 129 which carries also a cam arm 130 at the extremity of which 25 is a follower or roll 131 engaging a cam 132 on the main shaft 19. A spring 133 is arranged to pull frontwardly on the rock lever 128 thereby holding the cam roll to the cam.

With this arrangement each rotation of the 30 cam moves the rack 126 backward and frontward by a predetermined extent, the backward movement by the cam operating to rotate the feed shafts and rolls and thereby advance on to the applicers sufficient strip to form new headbands, the return movement of the 35 rack by the spring 133 being idle on account of the character of the drive clutch. The feed for the headband strips is to be timed to be completed before suction is applied to the 40 holder and before the operation of the severing devices. Adjustment of the extent of feed and length of headband may be effected by a stop rod 134, seen in Figs. 2 and 3, its threaded front end turning in a fixed nut or 45 sleeve 135, so that by a suitable handle the rod may be adjusted, for example backwardly, or to the right in Fig. 3, so as to limit and shorten the frontward movement of the lever 128 and thereby reduce the return 50 movement and length of feed, and vice versa.

For severing each pair of individual headbands from the fed strips, after each feeding action and after the suction has been applied, there is shown, at each end of the mechanism, 55 a cooperating pair of shearing blades mounted on adjusting carriages 137 at the left and 137^a at the right. Each of these carriages has an extension slidingly engaging the shaft 110, from which it receives its support. The 60 carriage 137 has a depending nut 54 already

mentioned as engaging the threaded shaft 51, while the carriage 137^a carries the depending nut 40 engaging the threaded shaft 37. Each carriage also has extending fingers 116 and 116^a engaging the hubs of the feed rolls; so 70 that when the shafts are turned the severing and feeding devices are adjustably shifted.

Each severing device includes a lower blade 140 and an upper blade 141, preferably the lower blade being relatively fixed on the carriage, while the upper blade swings downwardly to sever or shear the headband. The swinging blade is pivoted to the fixed blade by a pivot device 142 comprising spring means to maintain cooperating contact and pressure. 80 The movable blades 141 have, each at its inner end, actuating pins 143, and these two pins are shown as both engaged in the elongated horizontal groove 144 of a bar or cutter actuator 145.

The cutter actuator bar 145 is mounted at the top end of a carrier or shank 146 slidable vertically in fixed guideways, the lower end of the sliding shank being curved backwardly as seen in Fig. 3, and connected by links 90 or shackles 147 with the front end of a lever 148 fulcrumed on a fixed axle 149, the rear swinging end of the lever carrying a roll 150 engaged on the periphery of a cam 151 on the main shaft 19. The cam is shown as having 95 elevated the roll and depressed the carrier and actuator bar and thereby cut the headbands.

For the purpose of accurately alining or registering each of the headbands with the 100 ends of the book the following mechanism is disclosed. A movable registering device is employed, the same having a feeler or contact part adapted to be moved into contact with the end of the book and so determine the 105 position of the registering device and an adjuster which is positioned by the feeler and arranged to determine the position of the headband relatively to the book, either by adjusting the position of the applicer which 110 carries the headband to the book, or preferably by adjusting the position of the headband upon the applicer as they come to applying position.

While the registering devices may take different forms each of them is shown as a lever 115 170, extending substantially vertically, and arranged with a fulcrum 171 near its middle by which it is adapted to move to and from contact with the book. For example the registering lever may be mounted upon the headband applicer carriage 28, so that the lever 120 will bodily rise and fall and swing frontward and back with the carriage. In this way the lever is brought to position where it can make 125 contact with the end of the book, such contact being effected by swinging about its own fulcrum in a plane parallel to that of the book.

The topmost portion or tip 172 of the lever 130 constitutes the feeler and is arranged so that

when the parts are elevated it may swing inwardly to contact with the end of the book, as indicated in dotted lines at the upper right side of Fig. 2. Slightly below the tip 172 is shown the adjuster 173, which might be connected to adjust bodily the applier to bring the headband to position, but preferably is adapted to contact directly with each headband and thereby to position and adjust the headband on the applier in its correct relation to the book before being applied to the book, and for this purpose is shown as a cross plate or bar carried by the lever 170. The feeler or tip 173 determines from the book the position of the lever and of the adjuster, and thereby the headband, so that the predetermined relation between feeler and adjuster determines the relation between headband and book.

The registering member or lever 170 may be controlled in its swinging or registering movements as follows. It is formed with a lateral extension 174 which is pulled down by a spring 175 thereby tending to press the tip 172 toward the book. It is preferably moved and normally held away from the book by cam action, and only released when lifted into registering position. Thus at the outer side of the lever the edge 176 is in the nature of a cam which, at 177 falls away with a substantial incline. These two cam portions cooperate with a cam roll 179 projecting frontwardly from a plate or block 180 in such position that with up and down movements of the lever its edge or cam moves along the roll, thus controlling the swinging movements of the lever. The roll 179 may have vertical adjustment on the block 180, and the block may be mounted upon a fixed longitudinal bar 182 supported by brackets 183, and may be initially adjusted longitudinally on the bar to accord with the length of the book, the bar giving support to the blocks 180 at both ends. The relation of the roll 179 to the incline 177 times the swinging of the lever. The vertical adjustment of the roll alters the timing. After each operation the incline 177 retracts the lever, swinging its top end outwardly from the book.

The operation may be as follows. As the two appliers under timed control move or rise with the carriages 28, 28^a, they bring the headbands to the book, the headbands being held in position on the applier by the suction, which continues from before the severing until just an instant before or as the headband reaches the book. The cam edge 176 of each registering lever, bearing on the roll 179 holds outward or retracted the upper end of the lever until, as the carriages rise the edges 176 ride off the rolls, after the feelers 172 have risen above the level of the book back, so that the levers are then released under timed control and allowed to swing in-

wardly until the feelers contact the ends of the book, shortly before the completion of the rising movement. As the applying movement is being completed and each headband is being placed against the book, the registering lever, thus coming to position, adjusts the headband to the book. The headband is preferably initially fed to the applier slightly outwards of its desired position, so that at the moment of application the adjuster member 173 of the registering device contacts the headband and shifts it inwardly to exact position, permitted by the release of the suction; and in some cases this repositioning movement of the headband might even continue up to contact with the book, since the first pressure of the suction holder is light and the glue being wet may not oppose the shift. As a final result the headband is necessarily correctly applied to the book, with its outer or beaded edge overlapping the end of the book back by the predetermined amount.

In describing the illustrated embodiment the carriages and headband appliers have been referred to as being lifted or moving upwardly toward the book; this however not being intended as a limitation to the illustrated relation between the book and the applying mechanism, since the latter need not necessarily operate from beneath the book, but might operate from a different direction, so long as the applying action is in a direction toward the back of the book. Other relative terms are to be similarly considered.

The registration feature hereof is applicable to any strip or component to be applied to a glued book-back, such as the backlining which follows the application of the headbands, which must be correctly positioned lengthwise on the book back and which, as its applier brings it to the book may be registered at one or both ends by a device comprising the feeler and the adjuster of the present invention operating to adjust the component upon the applier so that it will be applied correctly to the book.

A book headbanding mechanism has thus been described attaining the objects and advantages recited. Since many matters of operation, combination and construction may be variously modified without departing from the principles it is not intended to limit the invention to such matters except to the extent set forth in the appended claims.

What is claimed is:

1. Mechanism for applying a headband to a book comprising a movable registering device or lever having a feeler adapted to contact the end of the book and so determine the position of the registering device and an adjuster positioned by the feeler and adapted to determine the position of the headband relatively to the book.
2. A mechanism for applying headbands

- to one or both ends of books held with their backs exposed, comprising an applier, means supplying headbands to the applier, a carriage carrying the applier and movable toward and from the book, and a headband registering device movable to and from registering position and comprising a feeler adapted to contact the end of the book and a connected adjuster adapted to position the headband in register with the book. 3. A mechanism for applying headbands to one or both ends of books held with their backs exposed, comprising an applier, means supplying headbands to the applier, a carriage carrying the applier and movable toward and from the book, and a headband registering device movable to and from registering position and comprising a feeler adapted to contact the end of the book and a connected adjuster adapted to position the headband in register with the book, by directly contacting the headband and positioning it on the applier before the applier applies the headband to the book. 4. A mechanism for applying a headband to a book, comprising an applier, a carriage carrying the applier and movable toward and from the book, and a headband registering device also carried on the movable carriage and thereon to and from registering position and comprising a feeler adapted to contact the end of the book and a connected adjuster adapted to position the headband in register with the book. 5. A mechanism as in claim 4 and wherein the registering device comprises a swingable lever mounted on the carriage, and means for swinging the lever to retract the feeler and adjuster and allowing them to return to registering position. 6. A mechanism as in claim 4 and wherein the registering device comprises a swingable lever mounted on the carriage, and a fixed cam device operative by reason of the movement of the carriage for swinging the lever to retract the feeler and adjuster and allowing them to return to registering position. 7. A mechanism as in claim 4 and wherein are means for adjusting the carriage, the applier and the registering device for books of varying length. 8. A mechanism as in claim 4 and wherein is automatic means for causing the registering and retracting movements of the device, and means for adjusting the timing thereof relatively to the movements of the carriage. 9. A mechanism for applying headbands to one or both ends of books held with their backs exposed, comprising an applier, means supplying headbands to the applier, a carriage carrying the applier and movable toward and from the book, timed means for moving the carriage toward and from the book, and timed means for swinging the carriage transversely to the plane of the book. 10. A mechanism as in claim 9 and wherein the means for swinging the carriage is a fixed cam operating by reason of the movement toward and from the book. 11. A mechanism for applying headbands to both ends of a book held with its back exposed, comprising an applier for each end of the book, means supplying headbands to the appliers, a pair of carriages carrying the appliers each having a hub, an axle part within each hub, the two axle parts being in screw threaded engagement with each other, means holding one axle part against rotation, means for rotating the other axle part at will to cause longitudinal adjustment thereof and of the hub and carriage supported thereon, and means for bodily shifting the axle parts to move the carriages and appliers toward and from the book. 12. A mechanism as in claim 11 and wherein is means for longitudinally adjusting the headband supplying means, and a single manual part for operating both adjustments. 13. A book headband applying mechanism comprising a carriage movable toward and from the book, a suction holder thereon and a shaper adjacent thereto, the suction holder consisting of a thin suction box with narrow suction slot, and the shaper consisting of a thin plate slidable alongside the holder. 14. A book headband applying mechanism comprising a carriage movable toward and from the book, a suction holder thereon and a shaper adjacent thereto, the suction holder consisting of a thin suction box with narrow suction slot, and means for adjusting the length of the slot. 15. A book headband applying mechanism comprising a carriage movable toward and from the book, a suction holder thereon and a shaper adjacent thereto, easily resilient means pressing the holder toward the book, and stiffly cushioning means pressing the shaper toward the book. 16. A mechanism as in claim 13 and wherein in the shaper has a rocking mounting for adapting it to the book. 17. In mechanism for applying headbands to both ends of a book back, an applier at each end, means feeding headband strip to each applier, a severing device adjacent each applier, and means for adjusting one or both appliers, with severing device, relatively toward or from the other for differing lengths of books, together with a common means for actuating both severing devices in any adjustment, consisting of an actuator bar parallel to the book back, means for moving the bar transversely to its length, and a movable connection from the bar to each severing device. 18. Mechanism for attaching to the glued back of books a backing or lining component, comprising a carrier movable toward and from the book back, means supplying such

components to the carrier, means for moving the carrier and component to the book, and a movable device registering the component to the book consisting of a feeler to contact the end of the book and a connected adjuster to position the component on the applier before the attachment of the component to the book.

In testimony whereof, this specification has been duly signed by:

ALFRED BREDENBERG.
